TELEPHONE DIAL WHEEL OR SIMILAR ARTICLE

David W. Hagelbarger, Morris Township, Morris County, N.J., assignor to Bell Telephone Laboratories, Incorporated, New York, N.Y., a corporation of New York

Filed Oct. 23, 1965, Ser. No. 87,879

Term of patent 14 years

(Cl. D26—14)

FIG. 1 is a perspective view of a telephone dial wheel, showing my new design; and

FIG. 2 is a detail view, to an enlarged scale, showing one of the pushbuttons depressed, the finger stop being omitted for convenience in illustration.

The dominant features of my new design are shown in solid lines in the drawing while the numerals and telephone desk set are shown in broken lines for illustrative purposes only.

I claim:

The ornamental design for a telephone dial wheel or similar article, as shown and described.
